WALL CONSTRUCTION

George H. Ellis, New Brighton, Minn., assignor to
 The Insulite Company, Minneapolis, Minn., a
 corporation of Minnesota

Application September 26, 1936, Serial No. 102,784

10 Claims.

(Cl. 72—32)

This invention relates to improvements in wall structures and particularly to the method of applying facing elements or boards in the construction of walls of buildings. The method may 5 be applied in relation to studdings or to the flooring stringers and facings that are ordinarily covered with plaster, cement or stucco. The invention also includes means for assisting in bonding plaster and the like to the board as well as to 10 assist re-enforcing and locking the joint.

This application is an improvement on my Patents 1,998,610 and 2,008,755.

Features of the invention include: the wall structure; the use of fibrous slabs or the like 15 in forming such structure; the bonding and re-enforcing elements or devices; the specific arrangement of the board or slabs to form the wall or the like; their proportionate lengths and widths in relation to the spacing distance between studding; the arrangement of the vertical joints on the studding; and generally all details of construction of re-enforcing element, and means for connecting it to the boards.

Other and additional objects of the invention 20 will be set forth in the description and the drawing which form a part of the application.

In the drawing:

Figure 1 is a face view showing one embodiment of the invention in the formation of a wall. 25 Figure 2 is a sectional view showing a plaster re-enforcing and joint locking means.

Figure 3 is a sectional view showing the invention applied to another form of joint.

Figure 4 is a sectional view showing an anti- 30 swinging staple.

Figure 5 is a view of a staple for securing the looped element to one of the slabs; and

Figure 6 is a perspective view of a plaster bonding and joint locking element. 35 Heretofore it has been customary to place the joint locking member directly against the plaster receiving face. This means gave a certain amount of plaster bonding by the locking means but not as much as desired. According to this 40 invention the joint is locked and greater plaster bonding is obtained.

In the drawing, numeral 10 indicates studding against which are laid slabs, preferably of fibrous material, 11, or other material, suitable for plaster 45 receiving base. The slabs are secured to the studding by means of suitable fastening devices, 12, generally nails. The length of the slabs ordinarily is about 48 inches, and the width ordinarily is about 18 inches. The long dimension of the 50 board is generally laid so as to be transverse to the studding and the abutting ends 13, of the contiguous boards of the horizontal rows takes place on the studding and these vertical joints need not be over-lapped but if desired they can be 55 so constructed.

The slabs are formed and laid to provide a shiplapped, horizontal, longitudinal joint, generally indicated at 16, see Figure 2, and for this purpose the opposite end of each slab 11, is cut out to provide a recess or notch at opposite longitudinal edges. There is no intention to limit the shape of the longitudinal elements, just so they are formed to provide over-lapped, and/or interlocked joints which give the greatest insulating value at the joint. 10

It is an important object of this invention as previously stated to increase the bonding of the plaster along the joint and at the same time reinforce and lock the joint.

When walls are constructed in accordance with 15 this invention there is a reduction of the tendency of plaster to crack along the joint as the re-enforcing means requires the plaster to be sufficiently thick to cover them and thus make it impossible to "skin the plaster". 20

In Figure 2 the plaster receiving base 11, has secured thereto joint locking elements which are provided with staple 14, which prevents the tendency of lock 15, to swing. The joint locking means may be of the type shown in Figure 6 25 but it is to be understood that the application is not limited to such construction but relates to a means for locking the joint and assisting in bonding the plaster. As long as the joint locking means efficiently locks the joint, the points 30 of contact with the plaster surface may be at the outer ends of the elements.

In Figure 3 is shown a modified form of overlapping joint 26, which may be used if desired. The element 15, is secured to the board 11, by 35 means of spikes 18, and the element 15 is prevented from swinging by means of staple 14, which is adapted to have the end 24, bend on the lower or under side of the board 11. The element 15, contacts the board by portions 17, 18 and 19 40 but it need not contact the board at more than two points. The plaster fills the spaces 22, between the element 15 and the board 11, thus insuring proper plaster bonding and in addition insures a proper thickness of plaster over the 45 whole plaster base. It is preferred that the staple 14, be placed in the depression 23, thus insuring that the staple will not be displaced.

It is to be understood that if a re-enforcing 50 and bonding element in the general shape as shown in Figure 4 of my Patent 1,998,610 of August 23, 1935 is used, the staple 14, is not required.

For the purpose of this application there has 55 been set forth certain structures and certain methods of using the same but it is to be understood that they are here presented for illustrative purposes only and are not to be accorded any interpretation such as might have the effect of 60

limiting what is claimed as the invention short of its true and comprehensive scope in the art.

I claim:

- 5 1. In combination with studding, slabs of material secured to and bridging the studding and formed to provide an overlapped joint which extends transversely of the studding, a plurality of plaster bonding and reenforcing structures each attached to one of two contiguous slabs and extending across the corresponding lapped joint and engaging the surface of each slab at spaced apart points whereby the major portions of said structures are held in spaced apart relation to the surface of the slabs, each of said looped structures 10 having prongs which are driven into one slab, and a staple securing the looped structure to that same slab at a point between the prongs and the joint.
- 15 2. A plaster-receiving base of fiber composition composed of a plurality of slabs formed and laid to provide an overlapped joint which can be opened by pressure applied against one face, and plural means arranged across the joint to assist in bonding plaster and to prevent opening as 20 the result of applied pressure, each means having two spaced arms, each arm having projecting portions to engage the surfaces of each board and each arm having a prong driven into one and the same slab whereby the arms are spaced from 25 the surface of the slabs to permit plaster to enter between the slabs' surface and the arms.

- 30 3. A plaster-receiving base of fiber composition composed of a plurality of slabs formed and laid to provide an overlapped joint which can be opened by pressure applied against one face, and plural means arranged across the joint to prevent opening as the result of such applied pressure, and to assist in bonding plaster, each means having two spaced arms the major part of the arms 35 spaced from the surface of the slabs, and each arm having a prong driven into one and the same slab and each arm provided with means extending from each arm to engage the surface of each board, and means to prevent swinging of each of 40 said plural means about the prongs as a center, said anti-swinging means being arranged between the prongs and the joint and being attached to the slab into which the prongs are driven.

- 45 4. A plaster receiving base of fiber composition composed of a plurality of elements laid in substantially coplanar relation to form a joint, and so that the elements can be pressed from coplanar relation with one another during application of plaster to one surface, and means arranged across the joint, and lying spaced apart and substantially parallel to one side of the plaster-receiving base, and contacting the base at spaced apart points whereby the major portion 50 of the means is spaced from the face of the base, and attached to one of the slabs acting to prevent the movement of one of the slabs to a non-coplanar relation with the other as the result of applied pressure.

- 55 5. A wall structure including studding, slabs of material secured to and bridging the studding and provided with overlapped joints which ex-

tend transversely to the studding, and a plurality of means attached to the plaster-receiving faces of the slabs and extending across the overlapped joints and engaging the faces of the slabs only at spaced apart points so that the major portion of the means is held spaced apart from the faces of the plaster receiving surface, thus preventing opening of the joints when plastering pressure is applied against the faces of the slabs in a direction toward and at points between the studdings and to aid in bonding the plaster.

5 6. In a wall, moisture absorbable, plaster-receiving base composed of a plurality of fibrous slabs provided with a longitudinal overlapped joint and rigid means on one face of the slab 15 extending substantially parallel to the face, and contacting the face only at spaced apart points whereby the major portion of the means is spaced from the faces of the slabs, extending across the joint to aid in bonding the plaster and prevent opening of the joint as the result of applied pressure.

20 7. A plaster receiving base composed of a plurality of expansible slabs of composition fiber provided with overlapped edges forming an air tight joint, and means of substantial width extending across the joint and engaging the faces of the slabs only at spaced apart points to hold the major portion of the means spaced from the surface of the slabs and to aid bonding the plaster and to prevent opening of the joint and introduction of plaster therein as the result of such applied pressure.

25 8. An article of manufacture comprising a sheet of composition board capable of acting as a plaster receiving base and provided with a tongue on one edge and a depression on the opposite edge to cooperate with a like sheet to form an overlapped joint, and means attached to one face of the sheet adjacent one edge and extending outwardly therebeyond, said means contacting the face of the sheet only at spaced apart points whereby the major portion of the means is held spaced from the surface of the sheets.

30 9. A wall structure including studding and sheets of plaster base material secured to and bridging the studding, and providing an overlapping joint capable of being opened by applied plastering pressure, and means arranged across the joint but not passing therethrough and contacting the sheet only at spaced apart points to hold the major portion of the means spaced from the surface of the sheets, and attached to prevent opening of the joint by such applied pressure, and to assist in bonding the plaster.

35 10. An article of manufacture comprising a composition board of fiber composition, a tongue on one edge and a depression on the opposite edge to cooperate with a like sheet to form an overlapped joint, and rigid means attached to one face adjacent one edge, and extending outwardly therebeyond, said means extending substantially parallel to the face and having projecting portions for contacting the face at spaced apart points whereby the major portion of the means is held 40 spaced from the surface of the board.

45 GEORGE H. ELLIS.
